UNITED STATES PATENT OFFICE.

JOSEPH VINCENT SHAW, OF DENVER, COLORADO.

SANITARY FOLDING CUP.

1,034,522.

Specification of Letters Patent.

Patented Aug. 6, 1912.

Application filed January 9, 1912. Serial No. 670,286.

To all whom it may concern:

Be it known that I, JOSEPH VINCENT SHAW, a citizen of the United States, residing at Denver, in the county of Denver and State of Colorado, have invented a new and useful Sanitary Folding Cup, of which the following is a specification.

One object of the present invention is to provide a collapsible cup that normally is of conical form, but which is adapted to be collapsed, the cup automatically expanding, to cause its mouth to assume an approximately circular form, thus best to adapt the cup for the purposes for which it is designed.

A further object of the invention is to provide a novel form of cover or closure for the cup, to hold the cup flattened or collapsed, and also to prevent an entrance of dust and other foreign material into the cup, when the same is not in use, the cover or closure being constructed in such a manner as to serve as a support for the cup, to hold the cup vertical, the cover serving further as a means for bracing the cup.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of what is claimed, without departing from the spirit of the invention.

In the drawings,—Figure 1 shows the cup in flat form, the view being a perspective; Fig. 2 is a side elevation of the cup with the closure applied thereto, parts being broken away; Fig. 3 is a longitudinal section of the cup, with the cover applied; Fig. 4 is a bottom plan of the cup; and Fig. 5 is a perspective showing the cup assembled with the cover, the cover being employed as a supporting base for the cup.

In carrying out the invention there is provided a cup 1, the same being collapsible and resilient, so as to stand in a normally distended position, as shown in Fig. 5. The cup 1 may be fashioned from spring metal, or from any other resilient substance. At its mouth, the cup 1 is preferably circular, as shown at 2, the bottom or apex of the cup being in the form of an oblong rectangle, as shown at 3. Corrugations or ribs are fashioned in the side wall of the cup, at dia-

metrically opposite points, as shown at 4, these ribs 4 serving to define longitudinal seats 5 in the interior of the cup.

A cover 6 is provided for the cup. The cover 6 includes a top 7, curved slightly as shown at 8, to conform to the curvature 9 of the upper edge of the cup, when the cup is in flat condition, as shown in Fig. 1. Projecting downwardly from the top 7 are side walls 10 and 11 which are preferably, although not necessarily, of triangular form. In the side wall 10 there is an opening 12, of the same contour as the base 3 of the cup, but slightly larger in extent than the base 3. At the ends of the top 7 there are converging fingers 14, the same preferably being concaved slightly. In the side walls of the cup 1 there are indentations 15, and in the side walls of the cover 6, there are similar indentations 16.

When the cup 1 is in folded condition, as shown in Fig. 2, the side walls 10 and 11 of the top or closure 6 overlie the outer faces of the cup, as clearly shown in Fig. 3. The converging fingers 14 will extend within the cup, and register in the seats 5. These fingers 14 constitute a means for holding the cup in the flat position shown in Fig. 1, and at the same time, the fingers 14 serve to reinforce the cup, so that it cannot be crushed and broken. The indentations 15 and 16, fashioned in the cup 1 and in the side walls of the cover, respectively, constitute interlocking elements adapted to hold the top or cover 6 upon the cup. If desired, the top 6 may be laid flat upon a support, the fingers 14 serving to increase the effective area of the top, and to prevent the top from overturning. The base 3 of the cup may then be inserted into the opening 12, whereupon the cup will be upheld in the position shown in Fig. 5.

Having thus described the invention, what is claimed is:

1. In a device of the class described, a transversely collapsible cup; and a cover for the cup, including side walls adapted to overlie the outside of the cup, and fingers projecting from the cover and engaging the side walls of the cup at spaced points adjacent the mouth of the cup.

2. In a device of the class described, a collapsible cup; and a cover for the cup, the cover comprising side walls adapted to overlie the outer face of the cup, and fingers projecting from the cover and adapted

to fit within the cup, there being longitudinal seats in the cup, adapted to receive the fingers.

3. In a device of the class described, a collapsible, resiliently distended conical cup; and a removable cover for the cup, including converging parts adapted to register within the cup, to flatten the cup, and to reinforce the cup.

10 4. In a device of the class described, a tapered, collapsible cup; and a double-walled cover for the cup, one wall of the cover being provided with an opening, adapted to receive the smaller end of the cup, whereby the cover may serve as a supporting base for the cup.

5. In a device of the class described, a collapsible cup; a cover for the cup, including a side wall having an opening adapted 20 to receive one end of the cup, whereby the cover may constitute a supporting base for the cup, the cover including diverging parts,

engaging within the cup, when the cover is mounted upon the cup, to effect a flattening of the cup, said diverging parts constituting means for preventing a tilting of the cup, when the cover is employed as a supporting base for the cup. 25

6. In a device of the class described, a conical cup; and a separable removable cover for the cup, the cover including fingers diverging toward the cover-proper and adapted to register within the cup, to effect a transverse flattening of the cup and to reinforce the cup, the cover being narrower 30 than the mouth of the cup, when the cup is in expanded condition. 35

In testimony that I claim the foregoing as my own, I have hereto affixed my signature in the presence of two witnesses.

JOSEPH VINCENT SHAW.
